UNITED STATES PATENT OFFICE.

JARED MARIS, OF COLUMBUS, OHIO.

DESIGN FOR A SHELL-BAND FOR WHEEL-HUBS.

SPECIFICATION forming part of Design No. 16,168, dated July 14, 1885.

Application filed May 20, 1883. Term of patent 14 years.

To all whom it may concern:

Be it known that I, JARED MARIS, a citizen of the United States, residing at Columbus, in the county of Franklin and State of Ohio, have 5 invented and produced a new and original Design for the Ornamentation of Shell-Bands for Wheel-Hubs, of which the following is a specification.

My invention relates to a design for the ornamentation of shell-bands for wheel-hubs; and 10 it consists in notches, scallops, or serrations on one or both ends of a shell-band comprising a hub.

In the accompanying drawings I have represented several different embodiments of my 15 design. Figure 1 illustrates a shell-band having on its inner end scallops A. Fig. 2 shows a band with its inner end provided with notches A. Fig. 3 represents a shell-band having its 20 opposite ends scalloped or notched, as at A A. Fig. 4 illustrates a shell-band provided with slight different-shaped notches or scallops; and

Fig. 5 represents a plan view of a hub, the ends of which are scalloped or notched, as at A A.

The notches or projections on the ends of the band may be varied in size and configuration; hence I do not restrict myself to the particular forms shown and described.

Having fully described my design, what I 30 claim as new, and desire to secure by Letters Patent, is—

1. In a design for shell-bands for a hub, the ornamentation of the same, consisting of notches, scallops, or serrations on one end of 35 said band, as shown and described.

2. In a design for a shell-band for a hub, the ornamentation of the same, consisting of notches, scallops, or serrations on both ends of said band, as shown and described.

JARED MARIS.
